UNITED STATES PATENT OFFICE.

EDWARD L. CALEY, OF PHILADELPHIA, PENNSYLVANIA, ASSIGNOR TO GILBERT COMBS, JOHN BAWDEN, AND JOHN H. BAWDEN, OF SAME PLACE.

DESIGN FOR A FIRE-PLACE LINING.

SPECIFICATION forming part of Design No. 18,896, dated February 5, 1889.

Application filed January 9, 1889. Serial No. 295,888. Term of patent 7 years.

To all whom it may concern:

Be it known that I, EDWARD L. CALEY, a citizen of the United States, and a resident of Philadelphia, Pennsylvania, have invented 5 a new and original Design for a Fire-Place Lining, of which the following is a specification.

My design for a fire-place lining is fully shown in the accompanying photographic illustration.

10 The design comprises both the back and side plates.

The general character of the design is that of a number of sections, each formed of foliated scrolls.

15 The design of the back plate is divided into two parts by a central dividing-bar, *a*. The border-bars, *b* *c*, at the top and bottom, are of substantially the same design as that of the central bar, and immediately above and below the central bar and immediately adjacent to the top and bottom bars are foliated bands of ornaments *d* *d*. Each of the upper

and lower panels is surrounded by a border, *e*, of plain lines ornamented at the corners and central parts. The longitudinal border-lines are connected at the center by a vertical ornament, *f*, dividing the panel into two sections, in each of which are three foliated scroll-bands, *g* *g'*, the central band, *g*, differing from the upper and lower bands, *g'*. The 25 side plates are of the same design as the back plate, with the exception that the designs are contracted in width.

I claim—

The design for a fire-place lining, substantially as described, and as shown in and by 35 the accompanying photographic illustration.

In testimony whereof I have signed my name to this specification in the presence of two subscribing witnesses.

EDWARD L. CALEY.

Witnesses:

WILLIAM D. CONNER,
HARRY SMITH.
